UNITED STATES PATENT OFFICE.

HARRY H. SCHROYER, OF CHICAGO, ILLINOIS, ASSIGNOR TO DUNBAR MANUFACTURING COMPANY, A CORPORATION OF ILLINOIS.

METALLIC CAR-DIAPHRAGM.

1,256,056.

Specification of Letters Patent. Patented Feb. 12, 1918.

Application filed April 10, 1918. Serial No. 90,134.

To all whom it may concern:

Be it known that I, HARRY H. SCHROYER, a citizen of the United States, and a resident of the city of Chicago, in the county of Cook and State of Illinois, have invented 5 certain new and useful Improvements in Metallic Car-Diaphragms; and I do hereby declare that the following is a full, clear, and exact description of the same, reference being had to the accompanying drawings, 10 and to the numerals of reference marked thereon, which form a part of this specification.

With the almost widespread introduction 15 of steel cars for passenger traffic on railroads, attempts have been made to construct metal vestibule diaphragms for attachment on the ends of the car which may be connected to one another to afford a sealed weather- 20 proof passage between the cars which are coupled together. Such a diaphragm must not only afford a weatherproof passage between the cars, but as well be capable of adjustment due to the severe conditions of 25 usage imposed thereon, owing to relative movement taking place between the coupled cars on which diaphragms of this type are mounted.

It is an object therefore of this invention 30 to construct a metallic car diaphragm wherein in the sides and top arching over the platform extension of the car are constructed of metal, the elements thereof being so designed and associated with one another as 35 to permit the necessary adjusting movements to take place when relative movements between the cars occur such as in traveling over an uneven roadbed, negotiating curves, or during switching operations.

40 It is also an object of this invention to construct a metallic car diaphragm comprising metal walls and top members integrally connected to one another and having the face plates sealingly and adjustably mounted thereon, and adapted to telescope within top and side wall members associated with the car to compensate for variations in movement between the coupled cars on which diaphragms constructed according to the 45 principles of my invention are mounted and connected to one another.

It is also an object of this invention to 50 construct a metallic car diaphragm wherein the side and top walls of the diaphragm are arranged to telescope with stationary re-

ceiving members mounted rigidly on the car and provided with sealing means and with the face plates of the diaphragm adjustably mounted on the outer end of said metallic top and side walls for relative movement 60 with respect thereto.

It is furthermore an important object of this invention to construct a metallic car diaphragm wherein integral top and side walls are deformed at their forward edges to 65 slidably and adjustably interfit with means mounted on a face plate forming a part of the diaphragm to permit adjusting movements of the face plate to take place and furthermore co-acting with sealing means to 70 afford a telescopic connection between the side and top walls of the diaphragm and the main body of the car to permit extension and contraction of the metallic diaphragm.

It is finally an object of this invention to 75 construct an improved type of metallic car diaphragm capable of extension and adjustment to compensate for inequalities and variations of alignment between coupled cars acting efficiently to afford a sealing connection for passage between the cars.

The invention (in a preferred form) is 80 illustrated in the drawings and hereinafter more fully described.

In the drawings:

Figure 1 is a vertical sectional detail taken through the upper end of a car showing a diaphragm embodying the principles of my invention.

Fig. 2 is an enlarged central detail view, 90 illustrating the telescopic sealing connection of the elements shown in Fig. 1.

Fig. 3 is a fragmentary detail section taken on line 3—3 of Fig. 1.

Fig. 4 is a fragmentary detail section 95 taken on line 4—4 of Fig. 1, with parts shown in elevation.

Fig. 5 is an enlarged fragmentary detail section showing the connection of the elements at one side of the construction shown 100 in Fig. 3.

Fig. 6 is a fragmentary detail section taken on line 6—6 of Fig. 1.

Fig. 7 is an enlarged detail section taken on line 7—7 of Fig. 4.

Fig. 8 is a detail section of a modified form of device.

As shown in the drawings:

The end of a car body is denoted as a whole by the reference numeral 1, and sec. 110

2

cured rigidly thereto at the upper end thereof is a horizontal flat metallic receiving compartment comprising a top wall 2, and a bottom wall 3, with the outer margins of the top wall 2, turned upwardly at right angles, as denoted by the reference numeral 4, and secured in any suitable manner to the body portion of the car. As clearly shown in Fig. 1, and the enlarged detail view in Fig. 2, thin metallic plates 5 and 6, respectively, are inserted into said compartment flat against the inner surfaces of the respective top and bottom walls 2 and 3, and have secured on each surface thereof a fabric or other sealing material, in the present instance shown preferably as strips of fabric belting, and denoted by the reference numeral 7. Extending downwardly of the car body, as clearly shown in Figs. 3 and 6, are thin compartments comprising an inner wall 8, and an outer wall 9, integrally connected to one another and with the upper margins of the inner wall 8, turned inwardly and rigidly secured to the bottom wall 3, of the upper horizontal compartment, and the upper margin of each of the outer walls 9, turned outwardly and rigidly secured to said bottom wall 3, said bottom wall 3, having a slot therein, as clearly shown in Fig. 3, at the junction of the upright walls 8 and 9, therewith. Angle iron braces 10, are secured to each of the outer walls 9, and to an upright I-beam frame member 11, forming a part of the car body. Inserted into the open end of the compartment afforded by the walls 8 and 9, are thin metallic strips 12 and 13, having belting or other sealing material 14, thereon.

The telescoping sections of the diaphragm 40 adapted to slide within the side wall and top compartments described, consist of side wall plates 15, adjustably connected as hereinabove described and shown in Figs. 3, 4, and 5, to a top wall plate 16. For this purpose, the upper margins of the respective side walls 15, are turned inwardly at a right angle, and secured on the under surface of the side margins of the top wall 16, are downwardly bent plates 18, to afford recesses 50 to receive slidably therein the inwardly turned margins 17, of the side walls, and a strip of sealing material 19, is secured upon the top surface of each of the inwardly turned portions of the side wall plates sealing against the under surface of the top wall plate 16. An adjustable connection is provided for both the side wall plates 15, and the top wall plate 16, at their forward or outer end at the connection thereof to a face plate 20. For this purpose, the forward margins of each of the side wall plates 15, are bent outwardly as denoted by the reference numeral 21, and shown in detail in Fig. 6, and beaded over, as denoted by the reference numeral 22. Secured upon the

rear face of the face plate 20, is a metallic strip 23, with one margin thereof bent outwardly and spaced away from the surface of the face plate to afford a recess for the reception of the beaded portion 22, of said side wall plate, so that the same fits snugly and sealingly therein and yet said face plate is capable of angular adjustment with respect thereto. The top wall plate 16, at its forward edge, is provided with an upturned margin 24, as shown in Figs. 4 and 7, which abuts against a wear plate 25, secured upon the face of the vestibule face plate and engages beneath a plate 26, secured thereto and with the margin thereof spaced therefrom and having a sealing strip 27, mounted therein to bear closely upon the upturned margin 24, of said top wall plate.

In the modification illustrated in Fig. 8, I have shown a slightly different construction from that shown in Fig. 6, wherein in place of the beaded portion of the shape designated by the reference numeral 22, in Fig. 6, is shown a rounded almost circular bead 28, formed on the bent margin 21, of the side wall plate.

The operation is as follows:

The side walls 15, and top wall 16, which telescope within the narrow side wall and top compartments secured rigidly on the car body, are sealingly and to some extent adjustably held therein and are capable of adjusting movements, so that the weaving effect which is imposed upon a diaphragm in use is readily taken care of without noise or wear upon the parts. As buffing and draft stresses take place between coupled cars, the respective diaphragm sections on the cars are contracted or expanded, as the case may be, the telescoping elements sliding one within the other. Due to the adjustable connection between the top wall and the side walls of the telescoping sections of the diaphragm, it is possible for one side wall to be extended or contracted a greater amount than the other, as for instance when a pair of coupled cars are traveling on a curved track or in switching, the top wall swinging laterally during such movement within the top wall compartment therefor, which is considerably wider than the top wall 16, itself to permit such swinging movement to take place. The face plate 20, is allowed to assume angled positions with respect to the telescoping sections of the vestibule diaphragm due to the yieldable connection between the top and side walls and said face plate, and furthermore said face plate is capable of sliding vertically to a certain extent to prevent strain being imposed upon the parts due to the weaving effect imposed upon the connected diaphragm sections of cars coupled to one another. The strips of sealing material shown consist of cotton belting, serving to effect a sealing connec-

tion between the respective parts of the diaphragm and furthermore to obviate noisy operation thereof.

It is obvious from the construction that 5 the diaphragm is comparatively easy to manufacture and assemble, and is simple in operation, and damage to any one of the parts thereof may be easily repaired by replacement.

10 I am aware that various details of construction may be varied through a wide range without departing from the principles of this invention, and I therefore do not purpose limiting the patent granted otherwise than necessitated by the prior art.

I claim as my invention:

1. In a metallic diaphragm construction of the class described, interfitting telescoping members, and a face plate associated 20 therewith and slidably adjustable with respect thereto.

2. In a diaphragm construction of the class described, the combination with metallic interfitting and telescoping members, 25 of sealing means associated therewith to seal the same in all positions of adjustment, and a connecting face plate to contact a corresponding face plate of another diaphragm vertically and horizontally 30 adjustably connected to said telescoping sections so as to be capable of adjustment with respect thereto.

3. In a metallic diaphragm construction of the class described, top and side wall 35 members adjustably connected to one another, compartment members secured to a car body adapted to receive said side wall members telescoping therewithin, and a face plate adjustably connected on said top and 40 side wall members.

4. In a metallic car diaphragm construction, adjustably connected top and side wall members, compartment members secured upon a car body adapted to receive said top 45 and side wall members telescoping therewithin, sealing means associated with said compartment members to seal said top and side wall members telescoping therewithin, and a face plate adjustably connected on 50 the forward end of said top and side wall members.

5. A car diaphragm of the class described, comprising top and side wall members, said top member adjustably connected to said 55 side wall members to permit relative movement therebetween, mechanism associated with the car body adapted to receive said top and side wall members telescoped therewithin, and a vestibule face plate adjustably 60 connected to the top and side wall members.

6. In a vestibule diaphragm of the class described, stationary upright channel side walls, thin plates inserted between the chan-

nel side walls, sealing material secured to each plate, a face plate, and flat upright side 65 walls hingedly connected thereto slidably interfitting in telescoping relation in said stationary channel side walls between the sealing material.

7. In a metal vestibule diaphragm of the 70 class described, the combination with stationary upright channel side walls, of a face plate, vertically and horizontally movable side walls pivoted to the face plate and slidably interfitting the channel side walls 75 and adapted to telescope therewithin, and sealing means interposed between said movable and stationary side walls

8. In a metal vestibule car diaphragm of the class described, stationary side walls each 80 having a recess therewithin, metallic strips secured to the side walls in the recess, sealing strips secured to the metallic strips, and hingedly mounted side walls extending between the sealing strips interfitting slidably 85 in telescoping relation with the stationary side walls.

9. In a device of the class described, stationary top and side channel members, a face plate, a top plate vertically adjustably 90 connected to the face plate adapted to slide into the top channel member, and side plates hingedly mounted on the face plate and 95 slidably vertically and horizontally with respect to the face plate adapted to telescope in the side channel members.

10. In a device of the class described, a face plate, top and side members connected to the face plate to slide relatively thereof, a pocket formed at each end of the top plate, 100 a flange on the upper end of each side member telescoping in said pocket, and top and side channel members fixed on the car into which the aforesaid top and side members slide.

11. A diaphragm comprising top and side channel members, a face plate, side members adjustably secured thereto extending into and forming a sliding connection with the side channel members, a top member having a sliding connection with the top channel member and the face plate, channels formed at the ends of the last named top member, flanges on the adjustable side members extending into the pockets and forming a 110 115 slideable connection with the top member, and a sealing material at all of the sliding connections.

In testimony whereof I have hereunto subscribed my name in the presence of two 120 subscribing witnesses.

HARRY H. SCHROYER.
